UNITED STATES PATENT OFFICE.

MARSHALL M. CRAM, OF MANKATO, MINNESOTA.

BOILER-CLEANER.

SPECIFICATION forming part of Letters Patent No. 634,521, dated October 10, 1899.

Application filed May 1, 1899. Serial No. 715,146. (No model.)

To all whom it may concern:

Be it known that I, MARSHALL M. CRAM, a citizen of the United States, residing at Mankato, in the county of Blue Earth and State of Minnesota, have invented a new and useful 5 Boiler-Cleaner, of which the following is a specification.

This invention relates to a device intended, primarily, for cleaning steam-boilers of sediment or mud which collects therein, although of course it can be employed with equal facility for the same purpose in connection with flues, tubes, and similar structures whereon scale is apt to form; and the object of the 10 invention is to provide an effective and light appliance of this character which occupies a comparatively small space in the boiler and which involves in its construction a series of communicating tubes or conduits, through 15 which the sediment can be ejected by the pressure developed in the boiler at short intervals and which can be moved back and forth, in said boiler by the application of a small amount of power to thoroughly remove 20 the objectionable substance.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in 35 which—

Figure 1 is a horizontal sectional plan view of a steam-boiler of ordinary construction inclosing a cleaning apparatus constructed in accordance with the invention. Fig. 2 is 40 a vertical longitudinal sectional side elevation of the boiler and the device therein. Fig. 3 is a transverse section taken in the line 3 3, Fig. 1, and looking in the direction of the arrow. Fig. 4 is a detail sectional view showing a modification of the adjusting mechanism for the piping. Fig. 5 is a detail cross-sectional view of one of the transverse 45 branch pipes.

Like characters denote like and corresponding parts in each of the several figures of the drawings.

In the drawings I have represented a steam-

boiler B of ordinary construction, and the device for cleaning the same is inclosed therein, and it involves in its construction a longitudinal or main pipe or conduit 2, disposed lengthwise of the boiler, and a series of three branch pipes or conduits connected with and extending oppositely from said main pipe.

In the drawings the main pipe 2 is shown 60 provided with three of the transverse branch pipes 3, thereby adapting the cleaner to a three-sheet boiler, although it will be understood that any desired number of the branch pipes may be employed as required for the 65 particular type of boiler in connection with which the apparatus is associated. In adapting the cleaner to a cylindrical boiler of the configuration shown in the drawings the branch pipes 3 are of a segmental curvature, 70 so as to agree in shape substantially with the shell of the boiler, and said branch pipes are adapted to lie in close proximity to the lower side of the boiler.

Each of the transverse branch pipes 3 is provided with a tapering lower side, in which is formed a continuous longitudinal slit 4, and at one side of the slit an edge of the pipe is extended to form a continuous longitudinal scraping edge 4^a, which is designed to engage 80 with the sediment clinging to the contiguous surface of the boiler-shell, so as to loosen the same up when the cleaner is adjusted and also serves to deflect the same through the slit 4 into the interior of the pipe, whence it 85 escapes through the main pipe 2. The several transverse branch pipes 3 are spaced at suitable distances apart and are connected for movement in unison with the main pipe 2, so that as the piping is moved back and forth 90 within the boiler the sediment or scale which has been deposited will be loosened up by the scraping edges 4^a and under the pressure within the boiler will be forced through the movable piping into a discharge-pipe, which 95 will be presently referred to.

The branch pipes are disposed crosswise of the boiler, and they are adapted to pass entirely along the same, each of them operating upon a sheet of the boiler, but not crossing the 100 joints between the plates.

The main pipe 2 is connected to the upper sides of the three branch pipes near their middles, and the end branch pipes are secured to

the extremities of the main pipe, while the intermediate branch pipe is located equidistant between the end branch pipes.

The discharge-pipe is denoted by 5, and it extends through one of the heads of the boiler and is located in parallelism with and is in communication with the main pipe 2, and it is provided beyond the head of the boiler with the blow-off valve 6, which can be opened when it is desired to clean the boiler, thereby to remove the accumulated sediment.

The elbow or bent pipe 7 is connected at one end by means of a universal coupling 8 of some suitable kind with the inner end of the discharge-pipe 5, and it is connected, likewise, by the universal coupling 9 with the short pipe 10, which in turn is connected with the upper side of the main pipe 2 near the middle of the same, by reason of which construction the material can escape from the boiler when the blow-off valve 6 is open, no matter what position therein the several transverse or branch pipes 3 may occupy, as the flexible connecting system just described maintains the proper communication between the main pipe 2 and the discharge-pipe 5.

In operation the cleaning attachment is moved back and forth in the boiler, and for effecting this action any convenient means may be employed, and in Figs. 1 and 2 the actuating mechanism includes in its organization a lazy-tongs 10^a of familiar construction, which is jointed at its inner end to the adjacent end of the movable attachment and is likewise coupled to the lug or bracket 12 within the boiler and upon what is herein illustrated as the left-hand head, whereby upon the operation of the said lazy-tongs corresponding movements of the cleaning device are obtained.

The lazy-tongs connection 10^a is extended and contracted by the fixed feed-screw 14, which extends through the stuffing-box 14^a in the head of the boiler and which is suitably fixed against endwise movement.

The threaded end of the screw 14 is embraced by the nut 15, which is secured to the lazy-tongs at a convenient point in its length and at the junction of two of its levers. The feed-screw is provided at its outer end with the hand-wheel 15^a, by which it can be rotated, thereby to effect the expansion and contraction of the lazy-tongs and the reciprocation of the cleaning device with the several branch pipes in proximity to the under side of the boiler, and at this time the blow-off valve 6 will be opened, so that the pressure in the boiler can force the sediment which collects upon the bottom of the boiler through the apertures 4 into the rigidly-connected parallel branch pipes 3, from thence into the connecting-pipe 2, and then into the discharge-pipe 5 through the pipe-sections 10 and 7, and the delivery end of the pipe 5 is disposed beyond the boiler and can of course be located at any point desired.

The device described can be advantageously

employed for cleaning all kinds of tubular and cylindrical articles; but when used in boilers the pressure generated therein can be utilized as the force for expelling the deposits, and it will be understood that any suitable organization of mechanism can be employed for drawing the cleaning device back and forth in the inclosing structure.

In Fig. 4 the framing or skeleton of piping is actuated through the agency of sprocket mechanism involving a primary power-shaft, the end of which can be located outside of the boiler and provided with a crank to turn the same.

The shafts 20 are supported within the boiler at opposite sides of the forward branch tube 3, and they are carried by bearings within the boiler, and one of them projects through a stuffing-box in said boiler and is provided with a hand-crank 21 to rotate the same. Said shafts 20 are provided with sprocket-wheels 22, located in the boiler and connected by a sprocket-chain 23, which in turn is secured to said front tube. By turning the crank-shaft 20 in one direction the tubular skeleton cleaning device can be moved one way, while rotating said crank-shaft in the reverse direction will result in moving the cleaning device in the opposite direction, and these actions will alternate until the boiler is thoroughly cleaned.

Changes in the form, proportion, size, and the minor details of construction within the scope of the appended claims may be resorted to without departing from the spirit or sacrificing any of the advantages of this invention.

Having thus described the invention, what I claim is—

1. A boiler-cleaner including a main pipe provided with a series of transverse pipes having slits or apertures therein, a discharge-pipe connected with said main pipe and passing through the boiler and provided with a valve, and a flexibly-jointed piping connecting said main pipe with the discharge-pipe, substantially as described.

2. A boiler-cleaner including a main pipe provided with a series of transverse pipes having slits or apertures therein, a discharge-pipe passing out through the boiler and connected with said main pipe by a universal coupling and provided with a valve, and means for operating the boiler-cleaner to move the same back and forth in a boiler, substantially as described.

3. A boiler-cleaner including a main pipe provided with a series of equidistantly-disposed transverse pipes having slits or apertures upon their under sides, a discharge-pipe connected with the main pipe and provided with a valve, a lazy-tongs secured to the main pipe, a feed-screw provided with a nut connected with the lazy-tongs, and a bracket to which said lazy-tongs is connected, substantially as described.

4. A boiler-cleaner including a main pipe provided with a series of equidistantly-dis-

posed transverse curved pipes having slits or apertures upon their under sides, a discharge-pipe connected with the main pipe and provided with a valve, a lazy-tongs connected with the main pipe, a feed-screw extending through a stuffing-box in the boiler and provided with a nut connected with the lazy-tongs intermediate its ends, and a bracket in the boiler to which said lazy-tongs is connected, substantially as described.

5. A boiler-cleaner including a longitudinal main pipe provided with a series of curved pipes extending oppositely therefrom having slits or apertures upon their under sides, a discharge-pipe provided with a valve, a flexible system of piping connected respectively with the main pipe and with the discharge-pipe, and means including a feed-screw, connected with the main pipe for moving the 15 same and the connected curved pipes along a boiler, substantially as described.

6. A boiler-cleaner comprising a main pipe having a plurality of transverse branch pipes provided in their lower sides with continuous

longitudinal slits extending from end to end 25 thereof, the sides of the pipe being tapered, substantially as described.

7. A boiler-cleaner comprising a main pipe having a plurality of transverse branch pipes provided at their lower sides with continuous 30 longitudinal slits, and also with continuous longitudinal scraping edges, substantially as described.

8. A boiler-cleaner comprising a movable main pipe having a plurality of transverse 35 branch pipes rigid therewith, each branch pipe being provided with a tapering lower side having therein a continuous longitudinal slit, and one side of the slit being extended to form a continuous longitudinal scraping edge, 40 substantially as described.

In testimony that I claim the foregoing as my own I have hereto affixed my signature in the presence of two witnesses.

MARSHALL M. CRAM.
